UNITED STATES PATENT OFFICE

EDWARD K. STANDISH, OF HARTFORD, CONNECTICUT, ASSIGNOR TO GRATON & KNIGHT COMPANY, OF WORCESTER, MASSACHUSETTS, A CORPORATION OF MASSACHUSETTS

THICKNESS GAUGING AND STAMPING MACHINE

Application filed June 27, 1928. Serial No. 288,786.

This invention relates to a machine for measuring the thickness of sheet material and for stamping an indication of such thickness on said material. While capable of general application, the invention is particularly useful in gauging leather hides, in which the thickness varies widely in different parts of the surface.

Such gauging and stamping of the leather is of great assistance to the operator who thereafter cuts the hide and assembles the pieces of leather for the manufacture of belting or other products. Accurate indication of the thickness of each unit portion at each such piece of leather permits substantial economy, by utilizing each piece of leather to its greatest useful thickness.

It is the object of my invention to provide a machine which will automatically gauge the thickness of a piece of sheet material fed thereto, and preferably having provision for stamping or impressing an indication of such thickness on said material.

A further object is to provide a machine which will automatically gauge and indicate such thickness at frequent and definitely spaced intervals as the sheet material, such as a hide of leather, is fed thereto. Preferably I provide a plurality of such gauging and stamping devices, spaced across the machine and all operated at definite intervals as the hide is fed through the machine, so that every unit area throughout the length and breadth of the hide will receive an indication showing the thickness of the hide for each such unit area. Obviously the gauging mechanism may be operated, independently of the stamping mechanism, to give a visual indication of thickness variation.

My invention further relates to arrangements and combinations of parts which will be hereinafter described and more particularly pointed out in the appended claims.

A preferred form of the invention is shown in the drawings in which

Fig. 1 is a front elevation of my improved machine;

Fig. 2 is an end elevation thereof, looking in the direction of the arrow 2 in Fig. 1;

Fig. 3 is a partial rear elevation, looking in the direction of the arrow 3 in Fig. 2;

Fig. 4 is a partial sectional end elevation, taken along the irregular line 4—4 in Fig. 3;

Fig. 5 is a detail end elevation of a gear 55 drive;

Fig. 6 is an enlarged side elevation of certain parts shown in Fig. 4;

Fig. 7 is a sectional plan view, taken substantially along the line 7—7 in Fig. 4;

Fig. 8 is an enlarged plan view of the upper feeding mechanism, looking in the direction of the arrow 8 in Fig. 1;

Fig. 9 is a sectional end elevation of the parts shown in Fig. 8 and looking in the direction of the arrow 9 in said figure;

Fig. 10 is a detail sectional front elevation, taken along the line 10—10 in Fig. 9;

Fig. 11 is an enlarged end elevation of the gauging and stamping mechanism, taken 70 along the line 11—11 in Fig. 1;

Fig. 12 is an enlarged detail front elevation, looking in the direction of the arrow 12 in Fig. 11;

Fig. 13 is an enlarged sectional plan view 75 of the gauging and stamping mechanism, taken along the line 13—13 in Fig. 12; and

Fig. 14 is a detail sectional elevation, taken along the line 14—14 in Fig. 13.

Referring to the drawings, my improved 80 gauging and stamping machine comprises a frame 20 (Fig. 1) supporting a table 21 over which the leather or other material L is fed as will be hereinafter described.

The table 21 comprises front and rear portions, as indicated in Fig. 4, separated by a supporting bar 22 and by two or more lower feed rolls 23. The bar 22 is firmly supported by a cross beam 25 and is preferably arched so that the leather will be drawn 90 firmly over the high point thereof.

Feeding mechanism

The lower feed rolls 23 are provided with pinions 26 (Fig. 5), each meshing with an 95 idle intermediate gear 27. One of the pinions 26 is engaged by a driving gear 28, which in turn is rotated by a pinion 29 on a shaft 30. The shaft 30 is provided with a ratchet wheel 31 (Fig. 6) engaged by a 100

spring plunger 32 yieldingly mounted in an arm or carrier 33 which swings loosely about the axis of the shaft 30.

5 A link 35 is pivoted to a stud 36 which is adjustable longitudinally of the arm 33 by an adjusting screw 37. By turning the screw 37, the effective length of the arm 33 may be varied. The link 35 has its lower end pivoted on a crank-pin 40 (Fig. 3) mounted in a disc 41 fixed on a cross shaft 42.

10 The shaft 42 is connected through reduction gearing (not shown) to a shaft 43 (Fig. 1) having a pulley 44 connected by a belt 45 to a pulley 46 on the armature shaft of a motor M which is mounted in fixed position in the machine and is supported by cross frame members 47 (Fig. 1).

15 By this construction, the crank-pin disc 41 is continuously rotated at relatively slow speed and the link 35, through the ratchet wheel 31 and the gearing above described, gives the feed rolls 23 frequently repeated intermittent feeding movements. The amount of feed at each graduation may be varied by 20 adjustment of the stud 36 along the swinging arm 33.

25 An idle gear 50 (Fig. 5) engages driving gear 28 and transmits motion to a pinion 51 on a cross shaft 52. The shaft 52 (Fig. 9) is mounted in suitable bearings 53 (Fig. 8) and supports a bevel gear 54 engaging a bevel pinion 55 on a short shaft 56 also rotatable in a fixed bearing in the frame member 57. The shaft 56 is connected by universal joint devices 58 (Fig. 8) to a shaft 59 provided with spiral gears 60 (Fig. 10) engaging similar gears 61 on two or more upper feed rolls 62.

30 The upper feed rolls are rotatable on suitable anti-friction bearings in a frame member 63 (Fig. 9) loosely mounted on a cross shaft 64 in a supporting arm 65 (Fig. 8).

35 The upper feed rolls 62 are thus intergeared with the lower feed rolls 23 and rotate in the same direction. One or more pairs of upper and lower feed rolls engage the leather at each side of the cross-bar 22, thus causing the leather to be firmly stretched by the separated pairs of feed rolls and to be firmly seated on the cross bar 22.

50 *Releasing mechanism*

Special provision is made for relieving the pressure of the front feed rolls, when it is desired to introduce a new piece of stock thereto. For this purpose the frame member 63 (Fig. 9) is connected by a link 70 to an arm 71 loosely pivoted on a cross shaft 72, to which the supporting arm 65 are secured.

60 The arm 71 has an upwardly extending portion 73 (Figs. 9 and 11) and is provided at its upper end with a hardened block 74 (Fig. 11), adapted to engage a shoulder 75 on a block 76 secured on an arm 77 mounted on a rock shaft 78. The shaft 78 is angularly 65 movable in bearings 79 (Fig. 3) and is pro-

vided with a depending arm 80 (Fig. 2), to the lower end of which is connected a link 81 having a turn-buckle 82 by which its length may be adjusted.

66 The link 81 is provided with a collar 84 at its outer end, engaged by a spring 85^a. A hand lever 86^a is pivoted at 87^a on the frame 70 20 and has a depending arm 88^a pivoted on collar 84. The spring 85^a normally holds the parts in the position shown in Fig. 11, with the arm 77 pressed downward to cause its block 76 to engage the block 74 in the upper 75 end of the arm 73.

75 When thus engaged, the link 70 (Figs. 9 and 11) is pressed downward, holding the 80 frame member 63 in normal or operative position. When the handle 86^a is depressed, the link 81 will be moved to the right in Fig. 2, raising the block 76 and releasing the arm 73. With the parts in this condition, the frame 85 members 63 may be easily rocked and the front feed rolls may be thus separated to permit insertion of a new hide of leather.

85 The parts are then re-latched by exerting 90 pressure manually on the supporting arm 71 (Fig. 9) until the lug 74 (Fig. 11) again engages the shoulder 75 on the block 76. I have thus provided for manually releasing the pressure so that the upper feed roll carriage may be rocked when a new piece of 95 leather is to be inserted and so that the normal pressure thereof may be quickly restored.

95 *Gauging and stamping mechanism*

The gauging and stamping mechanism is 100 shown herein as comprising a plurality of units G, spaced apart crosswise of the machine as indicated in Fig. 1.

105 I have shown these units as mounted in three pairs with feed roll units between adjacent pairs. A description of one gauging and stamping unit will apply equally to all of the other units.

110 Referring particularly to Figs. 11 to 14, each improved gauging and stamping mechanism comprises a stamping wheel 85 having numbers thereon indicating different thicknesses of material, the graduations commonly corresponding to differences of a sixtieth 115 of an inch in thickness.

115 The wheel 85 is mounted on a short shaft 86 (Fig. 13) rotatable in bearings 87 secured to the lower ends of plungers 88 (Fig. 11) vertically slidable in a fixed support 90. A spring 91 (Fig. 12) engages a cross-bar 92 connecting the upper ends of the plungers 88 and normally maintains the wheel 85 in raised position. A pinion 94 (Fig. 14) is formed on the shaft 86 and is engaged by a rack bar 95 mounted at the lower end of a rod 96 also slidable in the support 90.

120 A second rack bar 97 (Fig. 11) is formed at the upper end of the rod 96 and is slidable through the cross frame member 92. The 125 rack bar 97 is engaged by a segment gear 98

formed on a rock arm 99 pivoted at 100 and having a counter-balancing weight or arm 101. A spring 102 (Fig. 11) connects a stud 103 in the arm 101 to a stud 104 on an arm 105 secured to a rock shaft 106, oscillated by mechanism to be described.

A second stud 107 (Fig. 11) in the arm 105 provides a slidable bearing for a rod 108 having adjusting nuts 109 at its upper end.

- 10 At its lower end the rod 108 is connected to a bell crank 110, pivoted at 111, and having an offset portion adapted to engage a projection 112 on the outer end of a sliding latch 113. The latch 113 is slidable in a fixed bearing 114 and is pressed yieldingly outward to operative position by a spring 115. When in operative position, the latch 113 engages the lower face of the cross-bar 92.

When the arm 105 (Fig. 11) is raised by 20 rocking movement of the shaft 106, the spring 102 acts yieldingly to apply downward pressure to the rack bar 97, rotating the stamping wheel 185, by the engagement of the rack 95 (Fig. 14) with the pinion 94, while 25 movement of the cross-bar 92 is restrained by the latch 113.

If rotation of the stamping wheel is interrupted, the rack bar 95 and pinion 94 then form a rigid connection between the rack bar 30 97 and the stamping wheel 85. As the wheel is held from vertical movement by the cross bar 92 and latch 113, no further movement of the rack bar 97 can take place until the latch 113 is withdrawn. The spring 102 is placed 35 under increasing tension, as the upward movement of the arm 105 continues. The rod 108 is eventually raised, withdrawing the latch 113 and permitting the rack bar 97 and cross-bar 92 to descend quickly. Such 40 downward movement, due to the tensioned spring 102, is very abrupt and stamps the wheel 85 sharply against the surface of the leather.

Actuating mechanism

45 The mechanism for oscillating the rock shaft 106 comprises an arm 120 (Fig. 2) connected by a link 121 to an arm 122 on a lower rock shaft 123. An arm 124 (Fig. 4) is loose on the shaft 123 and is connected by a link 125 to a crank-pin 126 in a disc 127 secured to the opposite end of the shaft 42 (Fig. 3) previously described.

The arm 124 is thus regularly oscillated and 50 the hub 130 thereof (Fig. 3) is provided with clutch teeth co-operating with a clutch collar 131 keyed to the shaft 123 and yieldingly forced into driving engagement by a spring 133 mounted on the shaft 123 and engaging a collar 134 fixed thereon.

The sleeve 135 extends along the shaft 123 55 from the collar 131, and at its outer end is grooved as indicated at 136 in Fig. 7 to receive pins 137 in the yoke 138 mounted on an

upright shaft 139 rotatable in a fixed bearing 140 (Fig. 4).

A second arm or yoke 141 (Fig. 7) on the upright shaft 139 engages a collar 142 (Fig. 11), slidable on the rod or link 81 previously described. The spring 85^a on the rod 81 seats the collar 142 against a shoulder on the rod 81 but permits yielding sliding movement of the collar thereon. When the handle 86^a (Fig. 2) is raised, the collar 142 will be 70 moved to the left in Fig. 2 and to the right in Fig. 7, thus withdrawing the clutch collar 131 (Fig. 3) and preventing oscillation of the shaft 106 whenever desired.

A handle 150 (Fig. 2) is fixed on the rock shaft 123 and may be used for manually operating the stamping mechanism when the clutch is disengaged.

Gauge setting mechanism

I will now describe the mechanism for setting the impression wheel 85 to correspond to the thickness of the stock to be gauged.

For this purpose the wheel 85 is provided with a series of segmental abutments 152 80 (Fig. 13) positioned for engagement by the end of a stop arm 153, pivoted at 154 on a projection 155 (Fig. 11) of the frame 20.

A stud 156 (Fig. 13) on the hub of the stop arm 153 has a ball and socket connection with 85 a link 157 having a turn-buckle 158 at its center and having a ball and socket connection with a stud 160 (Fig. 11) in the upper end of an arm 161, mounted on a short shaft 162, provided with a second arm 163 having 90 a shoe 164 formed thereon and adapted to engage the upper surface of the leather to be measured.

A spring 170 (Fig. 13) is connected at one end to a stud 171 in the frame 20 and at the 100 other end to a stud 172 in the hub of the stop arm 153 and yieldingly resists upward movement of the shoe 164.

It will be noted that the shoe 164 is positioned directly over the high point of the 110 cross-bar 22 on which the belt rests as it is drawn between the pairs of upper and lower feed rolls 62 and 23. As the belt engages the shoe 164 and presses the same upward, the stop arm 153 is swung toward the segmental abutments 152 on the side of the impression wheel 85.

The movement of the stop arm 153 toward the segmental abutments depends directly upon the thickness of the leather under the shoe 164 and rotation of the wheel 85 will be 120 stopped by engagement with the stop arm 153 at a point corresponding to the elevation of the shoe 164 and consequently corresponding to the thickness of the leather under the shoe.

After rotation of the wheel 85 is thus stopped, the latch 113 is withdrawn and the wheel will be forced directly downward with an abrupt movement, marking the leather with the impression of the number which was 130

placed in printing position by the co-operation of the segmental abutments 152 and the swinging stop arm 153.

This setting and stamping operation takes place every time the shaft 123 is oscillated by its rotating crank-pin and takes place alternately with the feeding movement of the rolls 23 and 62, occasioned by the rotation of the second crank-pin 40. The parts thus move in timed relation, alternately feeding the leather, and then gauging and stamping the leather on selected units of its area.

Having thus described my invention and the advantages thereof, I do not wish to be limited to the details herein disclosed, otherwise than as set forth in the claims, but what I claim is:—

1. A device for gauging leather or other sheet material comprising, in combination, a gauge for measuring the thickness of the material, means for imprinting upon the material marks indicating the measurement ascertained by the gauge, and automatic means for intermittently feeding the material relative to the said gauge and said imprinting mechanism after each marking operation and for thereafter imprinting another mark thereon.

2. A device for gauging leather or other sheet material comprising, in combination, a gauge for measuring the thickness of the material, means for imprinting upon the material at or adjacent the point of contact of the gauge therewith the numerical value of the measurement ascertained by the gauge, and means for feeding the material relative to the said gauge and said imprinting means for repetition of the process.

3. A thickness gauging and stamping machine for leather hides and similar sheet material comprising a gauging and stamping device, means to feed said material intermittently by said device, and means to actuate said device intermittently to gauge said material and to stamp an indication of thickness thereon at regular spaced intervals.

4. A thickness gauging and stamping machine for leather hides and similar sheet material comprising a gauging and stamping device, means to feed said material intermittently by said device, and means to actuate said device intermittently to gauge said material and to stamp an indication of thickness thereon at regular spaced intervals, said feeding mechanism and said gauging and stamping mechanism operating alternately.

5. In a thickness gauging and stamping machine, a stamping wheel having a series of graduated abutments on its side face, means to turn said wheel, and means to variably engage said abutments and limit said turning movement in accordance with the thickness of the material being gauged.

6. In a thickness gauging and stamping machine, a stamping wheel, means yieldingly tending to give said wheel an excess turning

movement, means to limit said turning movement in accordance with the thickness of the material being gauged, and means to thereafter move said wheel abruptly toward said material to impress an indication of thickness thereon.

7. A device for gauging leather and other sheet material comprising in combination a gauge for measuring the thickness of the material, a reciprocating head, a stamping-wheel having figures upon its periphery and carried by said head into and out of contact with the surface of the material, means causing the gauge to rotate the stamping-wheel to present to said surface the figure having the proper value to represent the measurement being taken by the gauge, and means for feeding the material relative to the said gauge and stamping-wheel for repetition of such contact at spaced intervals upon the surface.

8. A machine for gauging the thickness of leather or other sheet material, comprising in combination a support, means for feeding the material over said support, and a plurality of gauging devices disposed across the course of movement of the said material, each adapted to record upon the surface of the material the thickness ascertained by it.

9. A machine for gauging the thickness of leather or other sheet material, in combination, means for feeding the material through said machine, a plurality of gauging devices disposed across the course of movement of the said material, each adapted to record at spaced intervals upon the surface of the material the thickness ascertained by its gauge, and means to actuate said gauging devices.

10. A thickness gauging and stamping machine for leather hides and similar sheet material comprising a plurality of gauging and stamping devices disposed across said material, means to feed said material by said devices, and means to actuate said devices intermittently to gauge and stamp the material whereby an indication of thickness is placed on each unit area of said sheet material.

11. In a thickness gauging and stamping machine, a stamping wheel, means including a spring for yieldingly turning said wheel, means to positively limit such turning movement, and means through which the same spring is thereafter effective to depress said stamping wheel to impress the material being gauged.

12. A thickness gauging and stamping machine comprising a gauging and stamping device, a feeding means, and means to alternately actuate said means and said device, whereby the material is gauged and stamped at predetermined spaced intervals.

In testimony whereof I have hereunto affixed my signature.

EDWARD K. STANDISH.
